(57) **CLAIM**

The ornamental design for a packaging sleeve assembly, as shown and described.

DESCRIPTION

FIG. 1 is a perspective view of a packaging sleeve assembly showing my new design;

FIG. 2 is a top plan view of the design of FIG. 1;

FIG. 3 is a bottom plan view of the design of FIG. 1;

FIG. 4 is a front view of the design of FIG. 1;

FIG. 5 is a rear view of the design of FIG. 1;

FIG. 6 is a left-side view of the design of FIG. 1;

FIG. 7 is a right-side view of the design of FIG. 1;

FIG. 8 is an exploded perspective view of the design of FIG. 1 showing an outer sleeve separated from an assembled internal sub-assembly comprising a top panel, a middle panel, a bottom panel, and two clamping strips, wherein the two clamping strips are identical;

FIG. 9 is an exploded perspective view of the internal sub-assembly of FIG. 8 showing the top panel, the middle panel, the bottom panel, and the two clamping strips, wherein the two clamping strips are identical;

FIG. 10 is a perspective view of the top panel of FIG. 9;

FIG. 11 is a top plan view of the top panel of FIG. 9;

FIG. 12 is a bottom plan view of the top panel of FIG. 9;

FIG. 13 is a front view of the top panel of FIG. 9;

FIG. 14 is a rear view of the top panel of FIG. 9;

FIG. 15 is a left-side view of the top panel of FIG. 9;

FIG. 16 is a right-side view of the top panel of FIG. 9;

FIG. 17 is a perspective view of the middle panel of FIG. 9;

FIG. 18 is a top plan view of the middle panel of FIG. 9;

FIG. 19 is a bottom plan view of the middle panel of FIG. 9;

FIG. 20 is a front view of the middle panel of FIG. 9;

FIG. 21 is a rear view of the middle panel of FIG. 9;

FIG. 22 is a left-side view of the middle panel of FIG. 9;

FIG. 23 is a right-side view of the middle panel of FIG. 9;

FIG. 24 is a perspective view of the bottom panel of FIG. 9;

FIG. 25 is a top plan view of the bottom panel of FIG. 9;

FIG. 26 is a bottom plan view of the bottom panel of FIG. 9;

FIG. 27 is a front view of the bottom panel of FIG. 9;

FIG. 28 is a rear view of the bottom panel of FIG. 9;

FIG. 29 is a left-side view of the bottom panel of FIG. 9;

FIG. 30 is a right-side view of the bottom panel of FIG. 9;

FIG. 24 is a perspective view of the bottom panel of FIG. 9;

(Continued)

FIG. 25 is a top plan view of the bottom panel of FIG. 9; FIG. 26 is a bottom plan view of the bottom panel of FIG. 9;

FIG. 27 is a front view of the bottom panel of FIG. 9; FIG. 28 is a rear view of the bottom panel of FIG. 9; FIG. 29 is a left-side view of the bottom panel of FIG. 9; FIG. 30 is a right-side view of the bottom panel of FIG. 9; FIG. 31 is a perspective view of a clamping strip of the two clamping strips of FIG. 9, wherein the two clamping strips are identical;

FIG. 32 is a right-side view of the clamping strip of FIG. 31; FIG. 33 is a left-side view of the clamping strip of FIG. 31; FIG. 34 is a top plan view of the clamping strip of FIG. 31; FIG. 35 is a bottom plan view of the clamping strip of FIG. 31;

FIG. 36 is a front view of the clamping strip of FIG. 31; FIG. 37 is a rear view of the clamping strip of FIG. 31; FIG. 38 is a perspective view of the assembled internal sub-assembly of FIG. 8;

FIG. 39 is a top plan view of the assembled internal sub-assembly of FIG. 8;

FIG. 40 is a bottom plan view of the assembled internal sub-assembly of FIG. 8;

FIG. 41 is a front view of the assembled internal sub-assembly of FIG. 8;

FIG. 42 is a rear view of the assembled internal sub-assembly of FIG. 8;

FIG. 43 is a left-side view of the assembled internal sub-assembly of FIG. 8;

FIG. 44 is a right-side view of the assembled internal sub-assembly of FIG. 8;

FIG. 45 is a perspective view of the outer sleeve of FIG. 8; FIG. 46 is a top plan view of the outer sleeve of FIG. 8;

FIG. 47 is a bottom plan view of the outer sleeve of FIG. 8; FIG. 48 is a front view of the outer sleeve of FIG. 8;

FIG. 49 is a rear view of the outer sleeve of FIG. 8;

FIG. 50 is a left-side view of the outer sleeve of FIG. 8; and, FIG. 51 is a right-side view of the outer sleeve of FIG. 8.
